UNITED STATES PATENT OFFICE.

CHARLES F. KETTERING, OF DAYTON, OHIO, ASSIGNOR, BY MESNE ASSIGNMENTS, TO
DELCO-LIGHT COMPANY, OF DAYTON, OHIO, A CORPORATION OF DELAWARE.

FUEL-SUPPLY DEVICE.

1,410,682.

Specification of Letters Patent. Patented Mar. 28, 1922.

Application filed September 28, 1918. Serial No. 255,294.

To all whom it may concern:

Be it known that I, CHARLES F. KETTERING, a citizen of the United States of America, residing at Dayton, county of Montgomery, State of Ohio, have invented certain new and useful Improvements in Fuel-Supply Devices, of which the following is a full, clear, and exact description.

This invention relates to devices for supplying fuel to internal combustion engines and the like.

One of the objects of the invention is to provide electrically operated means controlled by the operation of the engine for causing the delivery of fuel from a source of supply to a fuel reservoir from whence the fuel is sucked directly into the engine at each intake stroke thereof. One manner of carrying out this object consists in providing an electro-magnetic fuel pump including a magnet which is energized intermittently with the operation of the engine.

A further object of the invention is to provide a unitary structure including a fuel reservoir, and electrically operated devices for effecting the delivery of fuel from a source of supply to the fuel reservoir from whence the fuel is sucked into the engine.

A further object is to provide a unitary structure including electrical devices for controlling the delivery of the fuel charge to the engine in accordance with the operation of the engine.

A further object of the invention is to provide, in connection with an engine having a breather associated with the crank case and a fuel charge intake, a unitary structure which will serve as a connection between the breather and the fuel intake and which will include a fuel reservoir, a mixing chamber and devices for controlling the delivery of fuel to the fuel reservoir, and for controlling the delivery of fuel charge to the engine intake.

Further objects and advantages of the present invention will be apparent from the following description, reference being made to the accompanying drawing, wherein certain embodiments of the invention are shown.

Referring to the drawings:

Fig. 1 is an end view of an internal combustion engine showing the present invention applied thereto, together with a wiring diagram of certain electrical devices associated with the engine.

Fig. 2 is a sectional view showing on an enlarged scale the fuel supply and controlling devices shown in Fig. 1.

Fig. 3 is a sectional view taken on line 3—3, showing the throttle valve.

Fig. 4, the view taken on the line 4—4 of Fig. 2, showing the valve for controlling the admission of air.

Fig. 5 is a sectional view of a modified form of the invention together with a wiring diagram of electrical devices associated with this form of the invention and with the engine with which the invention is associated.

Referring to Fig. 1, 20 designates an internal combustion engine provided with a fly-wheel 21 which cooperates with the cylinder, not shown. Said engine 20 is provided with a breather 22, which is connected at the lower end with a crank case 23, and at the upper end with the fuel supply device 50, to be described. Said device 50 is connected with the intake pipe 24 of the engine. As will be explained later, the breather 22 and the member 50 provide passages from the interior of the crank case and from the outside atmosphere to the engine intake.

The fly-wheel 21 is provided with a pulley 25 which is connected by means of a belt 26 with the armature 27 of the generator 28. In general practice, it is usual to connect the armature directly with the crank shaft of the engine, but the belt connection is shown merely for purposes of illustration. The armature 27 is connected by wires 29 and 30 with the storage battery 31, and the shunt field winding 32 is connected across the wires 29 and 30. Wire 29 is connected by wire 33 with timer contact 35. Timer contact 34 which cooperates with timer contact 35 is connected by a wire 36, with a primary winding 37 of the ignition coil. The other end of winding 37 is connected by wire 38 with wire 30. The secondary winding 39 of the ignition coil is grounded by means of wire 40 on the engine, and connected at the other end by means of wire 41 with a spark plug 42. The opening and closing of the contacts 34 and 35 are effected by means of a timer cam 43 which is connected to the engine crank shaft by gear not shown.

Referring to Fig. 2, 50 indicates as a whole, a unitary structure comprising members 51, 52 and 53 which may be formed of cast metal and suitably joined together,

forming a single structure. The breather 22 is provided with inner and outer shells 22^a and 22^b. The inner shell 22^b is connected directly with the crank case of the engine 5 and leads into a passage 54, formed in the member 51. The shell 22^a surrounds the shell 22^b and forms a passage which communicates with the outside atmosphere through holes 22^c, see Fig. 1, and with the 10 passage 54 in member 51 through the opening 55. Thus it will be seen that air may be permitted to enter the passage 54 from the outside air and the crank case. The particular construction and operation of the 15 breathers forms no part of the present invention, but is described and claimed in my co-pending application Serial No. 146,825, filed February 5th, 1918. The member 51 is provided with a valve seat 56 having ports 20 57. A flat valve 58 having ports 59 is pivotally mounted upon the valve seat 56 by means of screw 60.

The member 52 is provided with a passage 61 which forms a continuation of the 25 passage 54, and said passage 61 leads upwardly to a restricted passage 62 which flares outwardly into a larger passage 63 which forms a mixing chamber in which the fuel charge is mixed with the air entering 30 the passage 61. The member 52 is provided with a chamber 64 which will be known as the fuel reservoir. The bottom of wall 65 of the reservoir 64 is provided with a downwardly projecting post 66, around which is 35 placed a solenoid magnet 67. One terminal of magnet 67 is connected by wire 68 with wire 38, and the other terminal is connected by the wire 69 with wire 36. The post 66 is bored out centrally to form a passage 70 which extends into a recess 71 formed in the 40 bottom wall 65 of the reservoir 64. A valve 72 having a notched flange is located within the recess and is yieldingly held in position by means of a spring 73 interposed between the valve 72 and a plug 74 mounted in the 45 upper wall 75 of the reservoir 64. The pump intake pipe 76 is secured upon the lower end of the post 66 and serves to support a plate 77 of non-magnetic material, upon which the magnet 67 rests. The member 52 is made of magnetic material and the pipe 76 of non-magnetic material. A solenoid armature 78 acting as a pump displacement member, is mounted to slide up and 50 down within the pipe 76 which serves as the pump cylinder. Said armature 78 is bored out centrally to form a passage 79, and a spring 80 is interposed between a shoulder 81 formed in the post 66; and a shoulder 82 formed within the armature 78. This 55 spring 80 serves to yieldingly maintain the armature in the downward position, as shown in Fig. 2. A ball check valve 83 located in the passage 79 serves normally to 60 maintain said passage closed. The pipe 76 65

is connected with an oil filter 84, and the pipe 85 connects the oil filter with an oil tank 86, which serves as the source of fuel for the engine. The reservoir 64 is provided with an overflow passage 87, which is 70 connected by means of pipe 88 with the tank 86. A portion of the reservoir 64 extends across the passage 61, in order to form the restricted passage 62. A plug 89 having 75 passages 90 and 91 provides a removable connection between the fuel reservoir and the mixing chamber 63. By securing the plug in the manner shown, it can be readily removed so that the passages may be easily cleaned. 80

The casting member 53 is provided with an outwardly extending apron 95 which provides a housing 96 for a solenoid magnet 97. The bottom of the housing 96 is closed by a plate 98 of non-magnetic material, provided 85 with a central aperture 99 through which slides a solenoid armature 100. One terminal of the magnet 96 is connected by means of a wire 109 with wire 38, and the other terminal by means of wire 110 with wire 29. 90

The casting member 53 is provided with a circular recess 101 in which is located a valve seat 102 which is provided with ports 103, which are segmental in shape. A valve 104 which is attached to the armature 100 is provided with segmental ports 105 and is located in the recess 101 and cooperates with the valve seat 102. The member 53 is provided with an auxiliary air valve 106, which is yieldingly maintained against a valve seat 107 by means of a spring 108. Valve 106 is located between valve 104 and the engine, so that the control of the air admitted by valve 106 will not be modified by the action of valve 104. 100 105

The operation of this form of the invention is as follows: As the engine operates the cam 43 will intermittently cause the opening and permit the closing of contacts 34 and 35. When the closing takes place, 110 current will flow through the wire 33, contact 34, contact 35, wire 36, primary ignition coil winding 37, wire 38, back to the wire 30. The coil 37 will be energized, and create a magnetic field in the region of the 115 secondary winding 39. The closing of the contacts 34 and 35 will also effect the energizing of the solenoid magnet 67, thereby causing the armature 78 to be attracted. Each revolution of cam 43 will effect the 120 separation of contacts 34 and 35, thereby causing an interruption of the flow to the primary winding 37 in order to create a 125 sparking impulse in the secondary winding 39, which is transmitted by wire 41 to the spark plug 42. The separation of the contacts 34 and 35 will also interrupt the flow of current to the magnet 67, and the same will be demagnetized. When this occurs the spring 80 will force the armature 78 130

into the lowermost position, as viewed in Fig. 2. Thus it will be seen that for every revolution of the cam 43, the solenoid armature 78 will move up and down. The upward movement of the armature 78 will cause any liquid which is contained in the passages 70 and 79 to be moved upwardly, and the pressure of the said liquid will maintain the valve 83 in position on its seat and will lift the valve 72 off its seat and cause some of the liquid to flow into the reservoir 64. Upon the downward movement of the armature 79, the valve 72 will return to its seated position and the ball valve 83 will be lifted to permit more liquid to enter the passages 70 and 79. Thus it will be seen that the up and down movement of the armature 78 will cause fuel to be pumped from the supply tank 86 to the fuel reservoir 64.

As the engine operates, due to the pumping action of the piston, air will be drawn into the breather through the holes 22^c and the passage 55, where it will be mixed with gaseous matter which may be drawn out of the crank case through the breather 22^b. This air will pass upwardly from the passage 61 and the passage 62, and at a point where the passage 62 flares out into the mixing chamber 63, a sucking action will be produced by the air as it rushes past the passages 91, thereby causing fuel to rise from the reservoir 64 up through the passage 90, and to flow out through the passages 91. This fuel will mix with the air in the mixing chamber 63 and will flow out through the openings 103 and 105, formed in the valve seat 102 and the valve 104, and into the intake 24 of the engine.

When the speed of the engine exceeds a certain amount the voltage between the wires 29 and 30 will exceed a certain value, and the magnet 96 will be energized sufficiently to begin to draw up the armature 100, thereby causing the valve 104 to move with relation to the valve seat 102, so as to begin to close the passage for the fuel into the engine. As the engine tends to rotate faster, the voltage will increase still further and cause the valve 104 to cut down the supply of fuel to the engine, and thus cause the engine to decrease in speed. The auxiliary valve 106 also has a governing effect by opening at a predetermined engine speed and cut down the richness of the fuel mixture. The amount of air entering the passage 61 is determined by the position of the valve 58.

Thus it will be seen in the foregoing description that there has been provided an electrically operated fuel pump of very simple construction, the movements of which are controlled by the action of the engine so that the fuel is pumped up from the

source of supply when the engine is running, and only sufficient quantities are retained in the reservoir to supply the engine with the required amount of fuel, according to the speed at which the engine is running. There has been provided a unitary structure which includes the pump and a carburetor or mixing chamber, and an automatic throttle valve controlled by the operation of the engine for limiting the speed of the engine to a certain predetermined value.

Referring to Fig. 5, showing a modified form of the invention, a hollow sleeve 120 of non-magnetic material has screw threaded engagement with the lower wall 65 of the reservoir 64. The lower end of sleeve 120 supports a plate 120^a of magnetic material, and is secured to the fuel intake pipe 76. A solenoid magnet 121 surrounds the upper end of the sleeve 120. One terminal 85 of said magnet 121 is connected by wire 122 with wire 29, and the other terminal is connected by wire 123 with a switch contact 124, which cooperates with switch contact 125. Contact 125 is connected by wire 126 to wire 30. A second solenoid magnet 127 surrounds the lower end of the sleeve 120 and one terminal of said magnet 127 is connected by wire 128 with wire 36, and the other terminal is connected by wire 129 with wire 38. Within the upper end of the sleeve 120 is placed a hollow plug 130 of magnetic material, and within the lower end of the sleeve 120 is placed a hollow plug 131 of magnetic material provided with a recess 132. The space in the sleeve 120, between the lower end of the plug 130 and the upper end of the plug 131 serves as a pump cylinder and is partially occupied by an armature 133, which serves as a displacement member. Washers 134 and 135 of non-magnetic material are interposed between the armature 133 and the plugs 130 and 131. The sum of the length of the armature 133 and the thickness of the washers 134 and 135 is less than the distance between the plugs 130 and 131, thereby permitting a certain amount of up and down movement of the armature 133. Said armature 133 is provided with a recess 136 in which is located a valve 137, similar in construction to valve 72. Valve 137 is yieldingly maintained in position by means of a spring 138, interposed between said valve 137 and the washer 134. The armature 133 is provided with a recess 139 in which is located one end of the spring 140 which serves normally to maintain a valve 141, similar to valve 137, within the recess 132 of the plug 131. In this form of the invention, the timer is provided with an extra set of contacts 124 and 125, as shown in Fig. 5, when the cam 143 permits the engagement of the contacts 124

and 125, current will flow through wire 126 across contacts 125 and 124 to wire 123 to magnet 121 and back through wire 122 to the wire 29. When this occurs the magnet 121 will be energized, thereby attracting the armature 133, causing the same to move to the position shown in Fig. 5. When this occurs, any fuel which is located above the valve 137 will be elevated and the valve 141 will be lifted from its seat. As the cam 43 rotates the contacts 124 and 125 will be caused to separate and the contacts 34 and 35 will be closed. When this occurs the ignition coil will be energized in the usual manner, and the magnet 127 will also be energized to effect the downward movement of the armature 133. When this movement takes place the valve 141 will be maintained on its seat, and the valve 137 will be moved away from its seat, due to the displacement of liquid by the downward movement of the armature 133. The washers of non-magnetic material 134 and 135 serve to maintain a gap between the armature 133 and the cores 130 and 131, in either position of said armature. Thus it will be seen that for each rotation of the cam 43, an up and down movement will be imparted to the armature 133, thereby causing the elevation of a certain amount of liquid from the fuel supply tank 36 to the reservoir 64. The pumping action of the engine will cause air to pass through passages 161, 162 and 163; and, at the juncture of the passages 162 and 163, fuel will be drawn out through the small hole 150, which connects with the passage 151 leading to the reservoir 64. A by-pass 155 is provided so that a certain quantity of air may be taken in passing the valve 104, without passing through the mixing chamber 163.

While the forms of mechanisms herein shown and described constitute preferred forms of embodiments of the invention, it is to be understood that other forms might be adopted, all coming within the scope of the claims which follow:

1. In a device of the kind described, the combination with an internal combustion engine having an intake; of a unitary structure including a passage for air into the intake, an electrically operated pump, and provisions for conducting fuel from the outlet of the pump to the air passage whereby the fuel may be mixed with air before passing to the engine.

2. In a device of the kind described, the combination with an internal combustion engine having an intake; of a unitary structure including a passage for air into the intake, an electrically operated fuel pump adapted to be connected with a source of fuel supply, a fuel reservoir connected with the fuel pump, and having an overflow passage adapted to be connected with the source

of fuel supply, and provisions for conducting fuel from the reservoir to the air passage, whereby the air may be charged with fuel before passing to the engine.

3. In a device of the kind described, the combination with an internal combustion engine having an intake; of a unitary structure including a passage for air into the intake, an electrically operated fuel pump, provisions for conducting fuel from the pump to the air passage whereby the air may be charged with fuel before passing to the engine, and an automatic throttle valve controlled by the operation of the engine to limit the amount of fuel charge delivered to the engine.

4. In a device of the kind described, the combination with an internal combustion engine having an intake and a breather associated with the crank case of the engine and adapted to be connected with the intake; of a unitary structure adapted to serve as a closure for the breather and provided with a passage from the breather to the intake, said unitary structure also including an electrical fuel pump and provision for conducting fuel from the pump to the passage whereby the air may be charged with fuel before being delivered to the engine.

5. In a device of the kind described, the combination with an internal combustion engine having an intake and a breather associated with the crank case adapted to be connected with the engine intake; of a unitary structure adapted to serve as a closure for the breather, and provided with a passage from the breather to the intake, said structure also including an electric fuel pump; provisions for conducting fuel from the pump outlet to the passage, an automatic throttle valve controlled by the operation of the engine for limiting the amount of fuel charge delivered to the engine at a given speed, and a manually controlled valve for controlling the amount of air delivered from the breather to the air passage in said structure.

6. In a device of the kind described, the combination with an internal combustion engine having an intake and a fuel source; of a unitary structure having a passage for air into the engine intake, said passage including a mixing chamber, said structure including a fuel reservoir connected with the mixing chamber and electrical devices controlled by the operation of the engine for causing fuel to be pumped from the fuel source to the fuel reservoir.

7. In a device of the kind described, the combination with an internal combustion engine having an intake and a generator driven by the engine; of a unitary structure having a passage for air to the engine, said passage including a mixing chamber, means

for supplying the mixing chamber with fuel, and electromagnetic means controlled by the generator for automatically limiting the amount of fuel charge delivered to the engine at a given speed.

8. In a device of the kind described, the combination with an internal combustion engine having an intake; of a unitary structure including a passage for air into the intake, 10 take, a fuel reservoir, a passage for fuel from the fuel reservoir to the air passage, a pump housing an end wall of which includes a portion of the bottom wall of the reservoir, an electromagnet located within the housing, 15 a magnetic core located within said housing and provided with a fuel passage therethrough communicating with the reservoir, a displacement chamber located adjacent said core and having a fuel inlet passage, a 20 displacement member having a passage therethrough; and valves controlling the passages.

9. In a device of the kind described, the combination with an internal combustion engine having an intake and a generator driven by the engine; of a unitary structure having a fuel reservoir; an air passage, a passage from the reservoir to the air passage, magnet housings located along the sides of 25 the air passage, a throttle valve controlling the intake and associated with electromagnetic controlling means connected with the generator and located within one of the magnet housings, and an electric fuel pump 30 including an electro-magnet controlled by the engine located within the other magnet 35

housing, said pump communicating with the fuel reservoir.

10. In a device of the kind described, the combination with an internal combustion engine having an intake and a generator driven by the engine; of a unitary structure having an air passage, magnet housings located along the sides of the air passage, a throttle valve controlling the intake associated with 40 electromagnetic controlling means connected with the generator and located within one of the magnet housings, and an electric fuel pump including an electro-magnet controlled by the engine located within the 45 other magnet housing, said pump communicating with the air passage.

11. In a device of the kind described, the combination with an engine having an intake; of a unitary structure comprising an 50 air passage, an electrically operated fuel pump, and removable means for conducting the fuel from the pump to the air passage.

12. In a device of the kind described, the combination with an engine having an intake; of a unitary structure comprising an air passage, a fuel reservoir, an electrically operated pump adapted to supply fuel to the reservoir, and removable means for conducting the fuel from the reservoir to the air 55 passage.

In testimony whereof I affix my signature.

CHARLES F. KETTERING.
